UNITED STATES PATENT OFFICE

LAVON D. MILLER, OF HICKSVILLE, OHIO

BENT WOOD HANDLE MANUFACTURE

Application filed February 19, 1930. Serial No. 429,602.

This invention relates to shaping material. This invention has utility in wood handle bending, especially in bending forked ends of sticks in providing crotch elements for

initial cut-out 9 and tapered terminus 10 is thus provided with a pair of tines 11.

wood handles, such as may be used on shovels, forks and other tools.

In this fork blank, is rivet 12 back of the

Fig. 9 is a detail view on a reduced scale of a handle hereunder.

Handle 18 may be shifted to connect the

Base 1 is shown as having loosely thereon die 2 having medial spreading tongue 3 into throat 4. From this throat 4 and along the sides of the spreading tongue 3 extend branched ways 5 to open ends 6 from which parallel cheeks 7 extend as continuations of the walls of the tongue 3. Stick 8 having

line 19 with exhaust line 26 independently of applying any further power to the cylinder 21. Handle 27 may then be operated to

connect fluid power from the line 17 to flow

by line 28 through cylinder head 15 into the

cylinder 16, thereby thrusting the die 2 with

its stick 8 in the contrary direction. This op-

eration is effective for partial recovery of the

piston rod 22.

Adjacent the openings 6, fixed guide blocks

29 for the die 2 are provided with upstand-

ing concave rolls 30 fixed in the region of

the openings 6 and effective in the travel of

the die 2 and the stick 8, carrying the spread

ends 24, to contact these spread portions in

applying a pressure transversely of the grain

of the stick of wood in thereby rebending the

tines of the fork from V-shape 24 to have

spread portions 31 extend to intermediate

bends 32 and there have free ends 33 approxi-

mate parallelism.

At this position with the rollers short of

the free ends of the V-terminus of the stick,

clamp 34 is applied. The stick 8, as steamed

or softened to reduce its tendency to frac-

ture and promote easy bending, is removed

with the die from this machine. To this end

handle 27 is oppositely operated to connect

line 28 with exhaust 35 and pressure line 17

with line 36 to cylinder end 37. There is thus

a retraction of the piston rod 14 clearing the die 2.

The handle 18 is now operated to again connect the fluid supply line 17 with the line 19 thus projecting the piston rod 22 in thrusting the die 2 with its stick past the rollers 30 so that the die with its clamp 34 in the unit of Fig. 5 may be set aside for partial seasoning or form-setting before removal of the clamp and die, thus allowing the stick to retain its complete form 38 (Fig. 9) wherein it may be completed by assembling therewith cross grip 39 as held by ferrules 40.

The handle 18 may again be turned to exhausting position for the cylinder 21, and stick 8 be applied to thrust the piston rod 22 back into the initial position for re-starting this cycle of operations in forming these handles.

20 Instead of the counter-thrust from the cylinder 16, the bends 32 for parallel portions 33 may be effected by operating piston rod 41 carrying yoke 42 engaging slides 43 in guides 44 of base 1 carrying rollers 30 (Fig. 6).

Again, instead of the piston rod 41 connected to yoke 42, thrusting action may be from links 45 on arms 46 (Fig. 7) of angle levers having fixed fulcra 47 on the guides 29 with free arms 48 folding or swinging toward each other in effecting the bends 32 for the parallel portions 33. Additionally, these parallel portions 33 may be brought into parallelism in the walls 7 by piston rods 49 oppositely acting thereon (Fig. 8).

What is claimed and it is desired to secure by Letters Patent is:

1. The method of producing a U-shaped fork from a piece of wood comprising notchting the wood lengthwise of the grain to form two tines, spreading the tines to V form by applying force between the tines toward the crotch of the V to effect straight diverging thereof, and thereafter the additional step of applying force spaced from the crotch of the V and on the outside thereof to move the diverging free end portions of the spreading tines inward toward each other into approximate parallelism.

50 2. The method of producing a pair of reverse bend curves in adjacent parallel grain wood portions integral at one terminus comprising spreading the portions into a V with the wood at the adjacent outside portion of the crotch concave with the termini straight and diverging, and spaced therefrom along the inner side of the crotch forming an additional opposite pair of concave portions by moving the V-free ends inward toward each other by a flexing effecting pressure.

3. The plural motion forming of a spread fork wood handle comprising pressing parallel to the handle grain along the grain of the inside of the fork toward the crotch to spread the wood into a V with the termini

straight and diverging, and then pressing parallel to the grain along the grain on the outside of the fork away from the crotch to bend the free ends of the V inward toward each other to approximate parallelism.

4. The method of bringing diverging straight free ends of a wood fork toward each other away from the crotch by bending toward each other the straight portion of the fork and locating such bending away from the crotch and away from the termini of the fork.

In witness whereof I affix my signature.

LAVON D. MILLER.
